To all whom it may concern:

Be it known that I, JOHN KEKKONEN, a subject of the Czar of Russia, residing at Chicago, in the county of Cook and State of Illinois, have invented a new, original, and ornamental Design for a Table-Bed, to be used when folded as a table and when unfolded as a bed, of which the following is a specification, reference being had to the accompanying drawing, forming part thereof.

concealed therein and showing my new design. Fig. 2 is an end elevation of the said table-bed. Fig. 3 shows the said table-bed in perspective.

Correction in Design Letters Patent No.
47,234.

It is hereby certified that Design Letters Patent No. 47,234, granted April 13, 1915, upon the application of John Kekkonen, of Chicago, Illinois, for a Design for a "Table-Bed," were erroneously issued to "Charles P. Monasch, as assignee by mesne assignments" whereas said Design should have been issued to *United Table-Bed Company, a corporation of Illinois, as assignee by mesne assignments of the entire interest*, as shown by the records of assignments in this Office; and that the said Letters Patent should be read with this correction therein that the same may conform to the record of the case in the Patent Office.

Signed and sealed this 18th day of May, A. D., 1915.

R. F. WHITEHEAD,
Acting Commissioner of Patents.
